(57) **CLAIM**

I claim the ornamental design for the handheld, inline induction heater, as shown and described.

DESCRIPTION

FIG. 1 is an isometric view of a handheld, inline induction heater showing my design;

FIG. 2 is a rear perspective view of the handheld, inline induction heater design shown in FIG. 1;

FIG. 3 is a front perspective view of the design shown in FIG. 1;

FIG. 4 is a top perspective view of the design shown in FIG. 1;

FIG. 5 is a left-side perspective view of the design shown in FIG. 1; and,

FIG. 6 is a bottom-side perspective view of the design shown in FIG. 1.

In the drawings, the broken lines depict unclaimed subject matter only and form no part of the claimed design.
